(57) **CLAIM**

The ornamental design for a vertical motor as shown and described.

DESCRIPTION

FIG. 1 is a front perspective view of a vertical motor embodying our design;

FIG. 2 is a rear perspective view of the vertical motor as depicted in FIG. 1;

FIG. 3 is a front elevation view of the vertical motor as shown in FIGS. 1 and 2;

FIG. 4 is a right side elevation view of the vertical motor as shown in FIGS. 1-3;

FIG. 5 is a left side elevation view of the vertical motor as shown in FIGS. 1-4;

FIG. 6 is a rear elevation view of the vertical motor as shown in FIGS. 1-5;

FIG. 7 is an enlarged top plan view of the vertical motor as shown in FIGS. 1-6; and

FIG. 8 is an enlarged bottom plan view of the vertical motor as shown in FIGS. 1-7.
